UNITED STATES PATENT OFFICE.

CHARLES A. AHLSTROM, OF JAMESTOWN, NEW YORK.

STRINGED MUSICAL INSTRUMENT.

SPECIFICATION forming part of Letters Patent No. 356,971, dated February 1, 1887.

Application filed November 24, 1886. Serial No. 219,820. (No model.)

To all whom it may concern:

Be it known that I, CHARLES A. AHLSTROM, of Jamestown, in the county of Chautauqua and State of New York, have invented certain new and useful Improvements in Stringed Musical Instruments; and I do hereby declare the following to be a full, clear, and exact description of the invention, such as will enable others skilled in the art to which it pertains to make and use it, reference being had to the accompanying drawings, which form part of this specification.

My invention relates to improvements in stringed musical instruments, but which is intended more especially for piano-fortes and other instruments of that nature; and it consists in, first, the combination of the regular strings for each note, the sympathetic strings used in connection therewith, and the piano-action with the under damper, which is operated by means of the arm and button which are attached to the damper-block; second, the combination, in the piano-action, of the damper-lever provided with an extension, a regulating-screw, and a button with the main arm or prop, the under damper-block pivoted in position so as to have a turning movement, a spring for returning the block to position after being moved, and the under damper, as 30 will be more fully described hereinafter.

The objects of my invention are to use, in connection with the regular strings for each note, one or more sympathetic strings, which are tuned in unison therewith, and which sympathetic strings vibrate when the regular strings are struck, agitated, or used, and thus produce sounds or tones that are not influenced in their character by the nature of the hammer or means employed to agitate or strike 35 the regular strings, thereby creating a greater volume and a purer tone than can be obtained where only the regular strings are used, to employ a separate and distinct set of dampers for each note, and thus dampen the regular and the sympathetic strings at the same time, and to employ a metallic agraffe for each note, and which is screwed into the iron frame, and which has four separate and distinct bearings—two for each string employed.

50 Figure 1 is a vertical detail section of a

piano to which my invention is applied. Fig. 2 is a plan view of the strings and the under dampers, showing the relative positions of the strings in relation to each other, the piano-action being removed.

A represents an ordinary metallic frame, such as is used in pianos; B, an ordinary piano-action; C, an ordinary sounding-board bridge, which is placed upon the sounding-board D. The metallic frame, the sounding-board, the bridge C, and the action B are all old, and hence need not be more fully described in this connection.

In the present instance I prefer to use three regular strings, E, for each note; but either a larger or smaller number may be used, if so preferred. These regular strings E are fastened at one end to the iron frame, passed through the metallic fastenings upon the bridge C, and then through the metallic agraffe F, which is 55 screwed into the iron frame A, as shown in Fig. 1. In connection with the regular strings E for each note, I use one, two, or more sympathetic strings, G, which are separated sufficiently far from the regular strings E so as not to be struck by the hammer H, or other means used to agitate or strike the regular strings E when the instrument is used. These sympathetic strings G are also fastened at one end and pass through the metallic attachments to 60 the bridge C, and then through the agraffe F in the same manner as the regular strings. These sympathetic strings G are tuned in unison with the regular strings E by means of the usual tuning-pins, I, and when the regular strings E are struck or agitated give forth 65 a unisonant sound, which greatly increases the duration, quantity, and quality of the tone.

The damper J is of the ordinary construction, and forms part of the action B and dampens the sound of the regular strings E in the usual manner. Rigidly secured to the damper-block B' is the arm or extension K, which projects a suitable distance beyond the end of the block, and through which is passed a regulating-screw, L, which has fastened to its inner end the regulating-button N, of the ordinary construction. This button N is made to brace 95 against a connecting arm or prop, O, which extends outward from the under damper-block 100

between the strings of each note, as shown in Fig. 2, and which arm or prop O serves to operate the under damper-block, P, which is pivoted to the metallic rail Q, which extends 5 across the frame under the strings. This rail has a series of extensions which catch in suitable grooves in the blocks P, and through these extensions are passed screws R, which serve to clamp or hold the clamps S to the underside of the rail, and between the extensions and the clamps are passed the pivotal pins T, upon which the blocks P turn. Connected to one end of the damper-blocks P are the felt dampers U, which serve to dampen the sounds 10 of the sympathetic strings G at the same time that the damper J serves to dampen the sounds of the regular strings E. In order to return each damper-block to position after it has been moved, there is attached to each block, at the 15 opposite end from the damper U, a suitable spring, V, which has its free end to bear upon the top of the rail Q, and thus instantly return the block P to position as soon as it is left free to move. When the button N strikes the arm 20 or prop O, the resistance of the spring V is overcome and the block P is made to turn upon its pivot T, and thus move the felt damper U away from the sympathetic strings G, and thus leave them free to vibrate. When the damper-block B' is returned to position by means of the spring C', the button N is made to press against the arm or prop O, and thus cause the block P to turn upon its pivot, and thus press the felt damper U in contact with the sympathetic 25 strings G, so as to dampen their vibrations. When the button N does not bear against the arm O, the spring V causes the block P to turn upon its pivot and move the felt damper U out of contact with the sympathetic 30 strings.

For each set of regular strings E and their accompanying sympathetic strings G there is provided a separate agraffe, F, which is screwed into the iron frame A, as shown in Fig. 1. The 35 top of each one of these agraffes is recessed at its center, so as to form two bearing-edges upon opposite sides, and through these bearing-edges are formed openings, as shown, so that the regular and sympathetic strings can be 40 given a double bearing in the agraffe without coming in contact or interfering with each other in any manner. These openings through the opposite sides of the agraffe allow the regular and sympathetic strings to be separated 45 sufficiently far from each other to prevent the strings G from being struck by the hammer H. The sympathetic strings G cross the regular strings E in passing through the agraffe, as shown in Fig. 1. Both the regular 50 and the sympathetic strings are the same length between the agraffe F and the sounding-board bridge C, and being tuned in unison, when the strings E are struck or agitated by any means, the strings G are made to vibrate in unison by 55 contact with the sounding-board bridge.

Piano-fortes manufactured at the present

time usually have two and sometimes three strings or unisons to each note. Tone is produced from these strings by means of a mechanism known as the "piano action," and more 70 particularly that part of the action known as the "hammer," which, by its striking against the strings at a certain predetermined point, causes the strings to both vibrate and sound, producing often a very harsh and metallic 75 quality of tone, varying always in its character from the nature of the material employed in the hammer.

The object of my invention is to obtain "sympathetically" musical sounds or tones 80 that are not influenced in their character by the nature of the hammer or means employed to agitate the strings, thereby creating audible and musical vibrations. By adding one or more sympathetic strings or unisons to each 85 note, placing said strings in firm contact with both the sounding-board bridge itself and through such parts as are commonly known as the "bridge-pins," or "sounding-board-bridge agraffe," or metal parts driven into or 90 attached to the sounding-board bridge, for the purpose of holding the strings in their respective positions on the sounding-board bridge, so that when the regular strings usually employed in musical instruments, and piano-fortes especially, are agitated or touched by any 95 suitable means, causing or exciting said regular strings into audible vibrations or musical sounds, said vibrations from the regular strings, of both equal duration and intensity, 100 are communicated to and reproduced by the sympathetic strings so added. The sympathetic strings being tuned in unison with the regular strings, the agitation created by and from the regular strings while the instrument 105 is being played upon puts the sympathetic duplex strings in free and powerful vibration, producing a unisonant sound with the regular strings when simultaneously or jointly employed, increasing the duration, the quantity, 110 and the quality of tone of each note to such an extent that a portion of the regular strings now alone employed in pianos, and which produce a harsher tone, can be dispensed with, and in their place utilize the sympathetic duplex strings of greater singing and penetrating 115 tone quality, and thereby greatly increase the durability and musical possibilities of the instrument. The quadruplex-bearing agraffe, already described, is indispensable to 120 my improvement for holding each string in its proper position and giving firmness and resource to the tone of the instrument.

I am aware that the use of sympathetic strings, auxiliary to the main strings, is old, 125 and this I do not broadly claim.

Having thus described my invention, I claim—

1. The combination of the regular strings for each note, the sympathetic strings used in 130 connection therewith, and the piano-action with the under damper, which is operated by

means of the arm K' and button, which are attached to the damper-block B', substantially as set forth.

2. The combination, in a piano-action, of 5 the damper-lever provided with the extension K, regulating-screw L, and button, with the arm or prop O, the damper-block P, pivoted in position so as to have a turning movement,

a spring for returning the block to position, and the damper U, substantially as shown. 10

In testimony whereof I affix my signature in presence of two witnesses.

CHARLES A. AHLSTROM.
